UNITED STATES PATENT OFFICE.

FRANK D. FRAZEE, OF SPRINGFIELD, ILLINOIS, ASSIGNOR OF ONE-HALF TO FRED A. MANNING, OF SPRINGFIELD, ILLINOIS.

BOW-PAD FOR VEHICLE-TOPS.

1,206,886.

Specification of Letters Patent. Patented June 17, 1919.

Application filed January 16, 1919. Serial No. 271,463.

To all whom it may concern:

Be it known that I, FRANK D. FRAZEE, a citizen of the United States, residing at Springfield, in the county of Sangamon and State of Illinois, have invented certain new and useful Improvements in Bow-Pads for Vehicle-Tops; and I do declare the following to be a full, clear, and exact description of the invention, such as will enable others skilled in the art to which it appertains to make and use the same.

This invention relates to bow-pads for vehicle tops, and it relates more particularly to an improved protecting strip which is attachable to automobile or carriage tops, between the covering of cloth or leather and the bows that support the cloth, so as to minimize the wearing of the cloth at the bows.

One object of the invention is to provide a pad of this character which is attachable to vehicle bows of all kinds and dimensions, and can be removed and replaced whenever necessary or desired.

Another object is to provide a pad of this character which may be manufactured in continuous lengths so as to be sold by linear measure, or in lengths each containing a sufficient number of length units to equip one or more vehicles therewith, thereby minimizing the cost of manufacture and also minimizing the waste in cutting the padding strips to the required units of length.

Other objects and advantages may become apparent to persons who read the following details of description in connection with the accompanying drawings, in which:

Figure 1 is an elevation, partly broken away, representing the top of an automobile equipped with my improved wear-reducing pads.

Fig. 2 is an enlarged perspective detail view illustrating the application of my improved pad more clearly.

Fig. 3 is a perspective detail view showing a portion of a vehicle bow in cross section and also showing my improved pad in cross section.

Fig. 4 is a cross sectional view on a still larger scale, illustrating the manner of securing my improved pad to the bow.

Referring to these drawings in detail, in which similar reference characters correspond with similar parts throughout the several views, the vehicle-top-bows 5 and cover

of cloth or other flexible sheet material 6 are shown merely to illustrate the application of the strip or pad which will now be described in detail as follows:

Referring especially to Figs. 3 and 4, the numeral 7 designates a hollow flexible tube of cloth or other sheet material, the same being filled with cotton lint or other suitable fibrous material 8. One or more rows of stitching 9 extends through the tube 7 and its filling 8 and depresses the tube and filling into a substantially flat strip or pad which is substantially equal in width throughout its length and is also substantially equal in thickness throughout its length. A strip 10 of cloth or fabric web has middle portion stitched to the middle portion of the pad 7-8; and it will be seen that the row of stitching 9 engages with the strip 10 to unite it with the pad 7-8 throughout the length of the latter, and moreover, it will be seen that the ends of the strip 10 may be turned back or lapped over the ends of the protecting pad as indicated at 10^a in Fig. 2. The lateral edge portions of the strip 10 may be turned inward and seated upon the outer base of the bow 5, and nails or other fasteners 11 may be driven therethrough into the bow 5 so as to unite the latter with the protecting strip.

Although the protecting pads may be manufactured in lengths just sufficient for covering the tops of the respective bows, as shown in Figs. 1 and 2, it is contemplated to form them in lengths much greater than necessary for covering the respective bow tops, so that a dealer in automobile supplies may measure off and sell a piece of protecting pad of any desired length, and the owner or repairer of the automobile may cut this piece into suitable lengths for application to the respective bows 5. In this cutting and fitting the protecting pads, a short piece of the pads 7-8 may be cut away from the adjacent end portion of the attaching strip 10, so that said end of the attaching strip may be turned back over the cut-away end of the protecting pad and stitched or nailed in place.

The protecting pad being flat, or being oblong in cross section, and substantially equal in width to the bow 5, it thoroughly protects the cover 6 from contact with the lateral edges of the bows 5, at the same time minimizing the tendency of the strip to roll

from the top of the bow 5 and become disengaged therefrom.

Although I have shown this embodiment of my invention attached to the bows of an automobile top, it is, of course, understood that it may be used in other relations than 5 has been shown and described. However, as this pad is especially useful in connection with vehicle bows, it is believed that its 10 principal use will be found in the connection shown and described.

Although this form of the invention has been described very specifically, it is not intended to limit the invention to the exact 15 details of construction, shape and dimensions described and illustrated, but I am entitled to make changes within the scope of the inventive idea disclosed in the foregoing description and following claims.

20 What is claimed as my invention is:

1. A pad comprising a flexible tube of substantially equal cross section at all points of its length, a flexible filling therein, and a strip of flexible material of substantially 25 equal width throughout its length, said strip having its longitudinal central portion stitched to that of the tube by means of

stitching that extends from end to end of the tube, the lateral edges of the said strip being free from the tube and adapted to engage with fastening means whereby it is attachable to a vehicle bow or other object. 30

2. The combination with a vehicle bow, of a flexible strip extending longitudinally along the top of the bow and having its edge 35 portions secured thereto and its longitudinal center free therefrom, a flexible tubular member secured to the free central part of the said strip, and a filling of flexible material in said tubular member. 40

3. The combination with a vehicle bow, of a flexible strip extending longitudinally along the top of the bow and having its edge portions secured thereto and its longitudinal center free therefrom, a flexible substantially flat tubular member extending along said strip, a filling of flexible material in said tubular member, and a row of stitching securing said tubular member in its flat condition and also securing it to said 45 strip. 50

In testimony whereof I have hereunto set my hand.

FRANK D. FRAZEE.
